10 The leading feature of my design for a badge is a body, A, having thereon a representation of a camp-kettle, a cross-pole, and crotch-poles sustaining the same, suggestive of army life.

15 A represents a badge consisting of an eagle, cross-cannons, and cannon-balls. On the badge is a representation of a camp-kettle, a, a cross-pole, b, from which the kettle depends, and upright crotch-poles c, which sustain the cross-pole. Beneath the kettle is a representation of fuel.
